PITCHER

Robert M. Mitchell, South Norwalk, Conn., assignor to General Foods Corporation, White Plains, N.Y., a corporation of Delaware

Filed Oct. 21, 1965, Ser. No. 87,706

Term of patent 14 years

(Cl. D44—21)

FIG. 1 is a side elevational view of a pitcher showing my new design;

FIG. 2 is a front elevational view;

FIG. 3 is a rear elevational view;

FIG. 4 is a top plan view.

The characteristic feature of my design resides in the particular configuration of the handle-equipped neck, collar and pouring lip portion of the pitcher.

I claim:

The ornamental design for a pitcher, as shown and described.
